UNITED STATES PATENT OFFICE

JOHN F. HOFFMAN, OF OMAHA, NEBRASKA, ASSIGNOR TO BAKER ICE MACHINE CO.
INC., OF OMAHA, NEBRASKA, A CORPORATION OF NEBRASKA

REFRIGERANT CONTROLLING APPARATUS

Application filed January 4, 1929. Serial No. 330,184.

My invention relates to refrigerating systems and more particularly to apparatus in which a volatile liquid is expanded by reduction in pressure in an evaporator such as a coil to produce the refrigerating effect, the principal objects of the invention being to relieve excess pressures in the system for preventing harm to operators and apparatus, to provide a permanently available outlet for fluid that may be trapped in an evaporating zone and subjected to heat, and to relieve flash gases that may accidentally be admitted into the supply line of the system toward an evaporator.

In some uses, for example when a liquid such as ice cream is to be cooled, it is desirable to flood the cooling surface in order to effect the most efficient operation by transfer of heat from a liquid to a liquid through the cooling surface. In such use sudden or excessive pressures may develop, particularly when the exhaust end of the evaporator is closed, as in one stage of operating ice cream freezing apparatus, and thus subject the apparatus to dangerous strain.

Further objects of the invention therefore are to provide for exhausting a charge of refrigerant confined in an evaporator, and to assure automatic relief of excess pressures.

In accomplishing these and other objects of the invention, I have provided improved details of structure, the preferred forms of which are illustrated in the accompanying drawings, wherein:

Fig. 1 is a perspective view of refrigerating apparatus including supply and return lines shown fragmentarily, and my improved safety device connected into the system.

Fig. 2 is a central vertical section of a valve for controlling the flow of refrigerant through the supply line, a tube forming part of a thermostatic control element being shown fragmentarily.

Fig. 3 is a side elevation partly in central section of an evaporator and my control device connected thereto.

Fig. 4 is a cross section of cooperating cylindrical trap members on the line 4-4, Fig. 3, illustrating the position of a thermostatic

loop in the chamber formed by the two members.

Referring in detail to the drawings:

1 designates generally an evaporator supported on a pedestal 2 and comprising a cylindrical container 3 and a cylindrical jacket 4 spaced from the container to form an annular vaporizing zone or chamber 5, such as employed for freezing ice cream, the zone corresponding to the interior of a refrigerating coil, and the specific structure representing apparatus with which the invention is particularly designed to be associated.

A pipe 6 leads from a source of refrigerant such as a compressor, not shown, and a valve 65 7 illustrated in detail in Fig. 2 and later described is mounted on the pipe 6 for controlling flow of refrigerant toward the evaporator through a supply line 8 connected to the valve and communicating at 9 with the 70 chamber 5.

A return 10 leading back toward the compressor is connected as presently described to the chamber 5 whereby the circuit is provided for passage of refrigerant through the annular chamber to exchange heat with the contents of the cylinder 3.

The above generally described structure is such as may commonly be found in systems of this character.

I preferably connect the supply line 8 to the chamber 5 at a relatively low point as indicated in Figs. 1 and 3 and connect the return at a high elevation to the chamber whereby refrigerant may flow in liquid state 85 through the supply line into the chamber and normally substantially flood the same, the refrigerant being evaporated therein and passing thence in vapor state through the return 10 toward the compressor.

A valve 11 is inserted in the return adjacent the evaporator for cutting off the flow of refrigerant from the chamber 5, for example, to cause an increase of temperature therein for well known purposes in the production of ice cream.

My invention includes an auxiliary reservoir 12 comprising preferably a cylindrical tank-like surge trap inserted in the supply line 8 and preferably having an inlet 14 at 100

its lower end into which the supply pipe is connected and an outlet 13 opposite the inlet.

I further preferably provide an enlarged portion 15 of the supply line for conducting 5 the fluid from the outlet of the reservoir 12 to the evaporator chamber.

Inserted in the return on the opposite side of the valve 11 from the evaporator is an 10 overflow trap 16 comprising a cylindrical casing having a greater diameter than the reservoir 12 and mounted over the same to form a partly annular chamber 17, the lower end 18 of the overflow trap being inbent and secured to the outer surface of the reservoir 15 in spaced relation with the bottom thereof as clearly shown in Fig. 3.

The upper end of the overflow trap extends upwardly beyond the reservoir 12, and 20 is closed by a removable cover 19. The outlet 20 from the overflow trap to the return is preferably located at a point above the upper end of the reservoir, while the inlet from the return to the trap is located adjacent the lower end thereof at 21, whereby fluid passing 25 from the evaporator enters the lower end of the overflow trap into contact with a portion of the reservoir and rises in the overflow trap toward the outlet 20 thereof for affecting interchange of heat between the fluids in the two members as later described.

A thermostat tube 22 extends into the overflow trap adjacent the outlet 20 and preferably includes a circularly bent portion 23 over which the rising fluid will pass on its 35 way to the outlet 20, the tube being extended through the wall of the trap and connected at 24 with the control valve 6, the tube being adapted to contain a temperature responsive fluid whereby changes of temperature in the 40 fluid in the overflow trap may cause expansion and contraction of fluid in the tube and influence the valve 6, as later described.

The reservoir 12 has a closed lower end 25 and its open upper end 26 is provided with a 45 sliding valve closure 27 having openings 28 closed by the wall of the reservoir when the valve is seated and adapted for passage of fluid when the valve is lifted under the influence of pressure in the reservoir. The valve 50 is retained on its seat and adjusted to respond to predetermined pressure values by a spring 29 mounted between retaining members 30 and 31 bearing respectively against the valve and a stem 32 screw-threadedly mounted in 55 an opening 33 in the cover 19 of the overflow trap. The stem is suitably packed to prevent escape of gases from the chamber 17.

The supply control valve 7 is described in detail in my co-pending application Serial 60 No. 299,393, and comprises a body 34 having a chamber 35 in its upper end, an annular recess 36 in its lower end forming a boss 37, and caps 38 and 39 having recesses 40 and 41 and binding diaphragms 42 and 43 to the 65 margins of the body recesses.

Fluid under pressure passes through an inlet 44 and channel 45 to the recess 36, displacing the diaphragm 43 against the regulating influence of a spring 46 in the cap 39 and moving through a port 47 into the central chamber, and thence through a channel 48 to the chamber 35 and to the outlet 49. 70

Flow through channel 48 is controlled by pressure of fluid in the cap recess 40 and tube 22 influenced by temperature in the overflow trap 16, and operating through diaphragm 42 on a fluted stem 50 in the channel 48 against a ball valve 51. 75

Fluid may be admitted to the cap 38 and thermostat tube 22 through a channel 52 in the body and cap, and the intake may be further controlled by back pressure in the evaporator side of the supply line by admitting fluid to the recess 41 of cap 39 through a channel 53, the portions of the channels 52 and 53 in the respective caps and the body communicating through suitable perforations in the respective diaphragms. 80

In operating apparatus equipped with control elements as described, for example when employed for freezing ice cream, the outlet valve in the return is normally open, and refrigerant will pass through the supply line to the evaporator in liquid state, and from the evaporator in vapor state to the casing 95 or overflow trap, leaving the trap in a slightly superheated condition. 90

The supply of refrigerant will be controlled responsively to changes in temperature of the departing vapor, through the thermostatic element including the tube coil and tube connected to the supply valve. 100

The relatively large trap will prevent escape of refrigerant in excessive quantities from the evaporator, should a "slop over" 105 occur, and the gas will pass from the trap in a dry state.

When the contents of the container have been sufficiently cooled, the cooling action may be stopped and a heating effect produced, by closing the outlet valve in the return, whereby pressure in the annular evaporator chamber is increased, with generation of heat, to warm the contents slightly and cause it to swell to bring about the desired overrun and produce a fluffy appearance and texture in the ice cream. 110

Pressure in the evaporator may however rise to a possibly dangerous value, and in such event the pressure will be relieved through the reservoir or surge trap, and through the pressure-responsive valve on the reservoir through which fluid may move into the larger enclosing overflow trap. 115

Steam may be passed into the container for washing and sterilizing the same while refrigerant is confined in the vaporizing chamber, without hazard, since excessive pressure due to quick or continued vapor- 120 125 130

zation of the refrigerant will be relieved through the elements mentioned.

The reservoir and casing above described further serve for exchange of heat between the contents thereof, for example, flash gas moving through the supply control valve to the reservoir, will pass upwardly to the top thereof, the reservoir wall conducting heat from the gas to the fluid in the overflow trap or casing, the gas passing into the casing through the valve of the reservoir where it will be condensed by direct contact and mixture with the cold gas in the casing.

What I claim and desire to secure by Letters Patent is:

1. In combination with refrigerating apparatus including a fluid supply line, an evaporator, and a return line, a surge trap communicating with the evaporator and having its lower end connected into the supply line and a casing connected into the return line and extending over the upper portion of the surge trap for exchange of heat between fluids contained by the surge trap and the casing.

2. In combination with refrigerating apparatus including a supply line, an evaporator, and a return line, a surge trap connected into the supply line and in permanent communication with the evaporator, a valve on the trap normally closing one end of the same responsive to excessive pressure therein, and a casing interposed in the return line adjacent the trap and adapted to receive fluid delivered through the valve.

3. In combination with refrigerating apparatus of the character described including an evaporating chamber, a supply line and a return line, a surge chamber member communicating with the supply line, and a casing communicating with the return line and mounted on said surge chamber member in spaced relation therewith for interchange of heat between fluid admitted to the surge chamber from the supply line and fluid admitted to the casing from the return line.

4. In combination with a circuit for fluid under pressure including a supply line and a return line, a normally closed relief valve operable by pressure in the supply line, and an overflow trap connected to the return line and having communication through said relief valve with the supply line upon operation of said valve for exchanging pressure values between the lines.

5. In combination with a circuit for fluid under pressure including a supply line, an expansion chamber, and a return line, a normally closed pressure relief valve responsive to pressure in the supply line, a casing connected to the return line surrounding said relief valve for affording communication between said casing and the supply line through said relief valve, and means responsive to changes in temperature in the casing for con-

trolling flow of fluid through the supply line.

6. In combination with refrigerating apparatus comprising a fluid circuit including a supply line, a return line, and a valve in the return line, a surge trap connected to the supply line and provided with a normally closed pressure relief valve responsive to pressure in the supply line, and an overflow trap interposed in the return line having communication with the supply line when said relief valve is open for relief of pressure in the supply line into said surge trap.

7. In a refrigerating system including an evaporating chamber and means for circulating a refrigerant including a supply line, a surge chamber member provided with a port and having a volume substantially equal to that of the evaporating chamber and in permanent communication therewith, and a pressure-actuated valve normally closing said port for relieving excess pressure in the surge chamber.

8. In a refrigerating system of the character described including an evaporating chamber, a supply line, a return line, and a valve in the return line for suspending flow of refrigerant from the evaporating chamber, a casing interposed in the return line on the opposite side of said valve from said chamber, and means including a normally closed pressure-actuated valve communicating with the supply line for relieving excess pressure in the evaporating chamber reversely through said valve into said casing.

9. In a pressure relief device for refrigerating apparatus including an evaporator, supply and return lines connected to the evaporator, and a manual control valve in the return line, a reservoir connected into the supply line and in permanently unobstructed communication with the evaporator, a pressure responsive valve on the reservoir, an overflow trap connected into the return line on the opposite side of said control valve from the evaporator and adapted to receive fluid from the reservoir through the pressure responsive valve, and means including an adjusted screw mounted in said overflow trap for adjusting the reservoir valve.

10. A pressure relief device for refrigerating apparatus including an evaporator, a supply line connected to the evaporator, a return line connected to the evaporator and having a cut-off valve, comprising a surge trap of capacity substantially equal to the capacity of the evaporator connected into the supply line in permanently unobstructed communication with the evaporator, and having a pressure responsive valve at one end, and an overflow trap connected into the return line on the opposite side of said cut-off valve from the evaporator and comprising a cylindrical body extending over a portion of the surge trap and having a lower end sealingly secured to the surge trap and an

upper end spaced from the valved end of the trap.

11. In combination with refrigerating apparatus of the character described including an evaporating chamber, a supply line, a return line and a supply control valve in the supply line, a surge chamber member communicating with the supply line, a casing communicating with the return line and mounted on said surge chamber member in spaced relation therewith, and means including a fluid-containing tube in said casing for controlling the supply line valve responsive to changes of temperature in the casing.
12. In refrigerating apparatus including supply and return lines and an evaporator, a surge trap having a lower end connected to the supply line and an upper end provided with a valve responsive to pressure in the trap, a conduit leading from the lower end of the surge trap to the lower side of the evaporator, a pipe leading from the upper side of the evaporator having an outlet end spaced below the inlet end of the return line and provided with a manually operable valve, and a casing surrounding the upper end of the surge trap to receive fluid passing from the trap through said valve thereon, and having a lower end portion engaged with said trap and communicating with said pipe and an upper portion communicating with the inlet end of the return line.
13. In combination with refrigerating apparatus including a fluid supply line, an evaporator and a return line, a surge trap constantly communicating with the evaporator and having its lower end connected into the supply line and a casing connected into the return line and extending over the upper portion of the surge trap for exchange of heat between fluids contained by the surge trap and the casing.

In testimony whereof I affix my signature.
JOHN F. HOFFMAN.
